UNITED STATES PATENT OFFICE.

HOWARD S. McMILLIN, OF ST. PAUL, MINNESOTA, ASSIGNOR TO METAL SCREEN & COTTAGE CO., OF ST. PAUL, MINNESOTA, A CORPORATION OF MINNESOTA.

PORTABLE COTTAGE.

1,008,483.

Specification of Letters Patent. Patented Nov. 14, 1911.

Original application filed September 20, 1909, Serial No. 518,461. Divided and this application filed July 11, 1910. Serial No. 571,415.

To all whom it may concern:

Be it known that I, HOWARD S. McMILLIN, a citizen of the United States, residing at St. Paul, in the county of Ramsey and State 5 of Minnesota, have invented certain new and useful Improvements in Portable Cottages, of which the following is a specification.

My invention relates to improvements in knockdown cottage or tent frames, its object 10 being particularly to provide an improved form of clamp for holding together the upper corners of the frame and adjacent portions of the inclined roof rafters, and consists in the features of construction, combination and arrangement of parts herein-after particularly described and claimed, this application being divisional of my application filed September 20, 1909, Serial Number 518,461.

20 In the accompanying drawings forming part of this specification, Figure 1 is a perspective view of my improved corner bracket shown in use; Fig. 2 is a detail view of the blank for forming the main member of the 25 bracket; and Fig. 3 is a detail view of the other member of the bracket.

Referring to the drawings A represents the corner uprights of the framework, B the horizontal bars constituting the tops of the 30 side and end walls, and C the inclined rafters for the roof.

My improved bracket is made up of two coöperating members D and E. The member D is of right angle shape in horizontal 35 cross section to fit flat against the outer sides of the upright 4 and the outer faces of the supported corner ends of the horizontal beams B. One side of the bracket member D is formed with an upwardly extending 40 flange 2 having its upper edge inclined to fit underneath, and form a support for, the rafter C. The free side edge 3 of the flange 2 is inturned so that the bottom of said inturned edge 3 will rest upon the top face 45 of the adjacent horizontal beam B with the upper edge of said inturned portion 3 in contact with the underside of the roof rafter. The roof rafter, which is preferably 50 of angle iron, at its lower end receives and rests upon the upper edge of the flange 2, being secured thereto by bolts or other suitable securing means passed through the

openings 4 in the bracket and rafter. The bracket member D is similarly secured to the upright A and horizontal beams B. The 55 coöperating plate E of the bracket is shaped to fit closely into the space formed by the two side walls of the bracket and the in-turned end 3 of the flange 2, said plate lying flat on the top faces of the beams B. The 60 plate E is secured to the framework by bolts or other suitable securing means passed through openings 4 in the plate and framework.

With the bracket secured in the position 65 shown and the plate E wedged into the space between the side walls of the bracket and inturned end 3 it will be evident that the horizontal beams B, upright A and rafter C will be firmly clamped together and 70 braced against twisting and sagging. The bracket also so supports the members and framework that there is the minimum of strain upon the securing bolts and a framework construction obtained of the strongest 75 and most rigid character.

I claim as my invention:

1. In a collapsible knockdown cottage of the class described, a plurality of wall sections, a sloping roof support, and a bracket 80 overlapping meeting corners of said wall sections and having an upwardly extending flange inclined to correspond with and support said roof support, the free side edge of said flange being inturned underneath said 85 roof support.

2. In a collapsible knockdown cottage of the class described, a plurality of wall sections, a sloping roof support, a bracket overlapping meeting corners of said wall sections and having an upwardly extending flange fitted underneath said roof support, the free side edge of said bracket being in-turned underneath said roof support, and a plate fitted between said flange and in-turned edge and the opposite wall of said bracket above said wall sections.

In testimony whereof I affix my signature in presence of two witnesses.

HOWARD S. McMILLIN.
